UNITED STATES PATENT OFFICE.

CHARLES K. POYNER, OF PADUCAH, KENTUCKY.

MACHINE FOR UNITING KNIT FABRICS.

1,203,404.

Specification of Letters Patent. Patented Oct. 31, 1916.

Application filed December 13, 1915. Serial No. 66,476.

To all whom it may concern:

Be it known that I, CHARLES K. POYNER, a citizen of the United States, residing in Paducah, McCracken county, State of Kentucky, have invented an Improvement in Machines for Uniting Knit Fabrics, of which the following description, in connection with the accompanying drawings, is a specification, like letters on the drawings representing like parts.

My invention relates more particularly to machines for uniting knit fabrics, in which the feeding action is continuous rather than intermittent.

An illustrative embodiment of my improved mechanism is shown in the drawings accompanying this specification, in which,

Figure 1 is a front elevation of a machine for sewing together the edges of looped fabrics with the looper-point dial and other portions of the machine broken away or omitted to show clearly my improved feeding mechanism; Fig. 2 is a detail view illustrating the preferred shape of cam for operating the mechanism which moves the needle carrying arm in a lateral direction; Fig. 3 is a side elevation of a machine for sewing together the edges of looped fabrics, parts being broken away to show details of the dial actuating mechanism, and, Fig. 4 is a detail view illustrating the adjustable rod guide forming a part of the dial actuating mechanism.

It is well known that machines for uniting knit fabrics, in which the dial movement is intermittent, present a serious difficulty to the operators in that the uneven movement interferes greatly with the positioning of the knitted fabric upon the hopper points of the dial. It is contemplated that this difficulty may readily be overcome by providing a dial actuating mechanism which will permit continuous rotation of the dial. A further improvement in this class of machines is suggested by the fact that those commonly in use at the present time are not readily adapted to operate upon fabrics of different mesh gage or loop size. Ordinarily it is necessary to provide a separate machine for each size of mesh. Thus, in a factory where many gradations of knitted fabrics running from fine to coarse mesh are made, a correspondingly large number of machines will be required.

In view of the difficulties outlined above in connection with the operation and adapt-

ability of such machines now in use, I have devised an improved dial actuating mechanism which not only permits the looper-point dial to be rotated continuously, but which is readily adjustable to vary the speed of the dial, so that, in a single machine, dials of different gage may be interchangeable and adapted to be actuated by the same driving mechanism.

In the embodiment of my invention illustrated in the drawings, a looper-point dial 1 is mounted upon a suitable frame in such a manner that it may rotate across the path of a reciprocating needle 2. In order that the rotation of the dial may be continuous, I provide suitable actuating means which include a main power shaft 3 having a series of cams 4, 5, 6 and 7 mounted upon it, corresponding portions of said cams being successively effective at intervals of substantially 90° in the rotation of said shaft. The dial 1 is provided with a rack 8, which is adapted to engage a pinion 9 fixed to a drive shaft 10. Rotation of this shaft may be effected by means of a succession of ratchets 11, 12, 13 and 14 which are mounted upon the shaft 10 in stepped or off-set relation, the extent of the off-set in the illustrated embodiment being substantially one quarter of a tooth in each successive ratchet. Pawls 15, 16, 17 and 18 engage the ratchets 11, 12, 13 and 14 respectively, said pawls being pivotally mounted on suitable lever arms, as 19.

Referring to Fig. 3, the operation of the pawl and ratchet mechanism may be more clearly understood by explaining a typical illustrative arrangement, including the ratchet 11 and the pawl 15 which is pivotally mounted on a lever arm 19, the latter being conveniently pivoted to the framework of the machine. Normal pawl actuating movement of the lever arm 19 is accomplished by the alternate thrust and pull of a rod 20 which engages the said arm pivotally. The cam 4 engages a wiper 21 which communicates its reciprocatory motion to a link 22 and thereby to the rod 20, thus actuating the cam 15 and the ratchet 11. By means of the ratchets and pawls actuated in succession by the cams as described, the shaft 10 receives a steady continuous motion free from any jerk or rebound due to impact from the actuating members.

Where it is found necessary to alter the machine in order to accommodate work of a different mesh gage from that of the fabric

previously sewed, the dial 1 may be removed and replaced by a similar dial of different gage. Assuming that the new dial is of a gage adapted to receive fabric of a coarser 5 mesh than that accommodated by the previous dial 1, it is obvious that the new dial must be rotated at a greater speed than the previous smaller gage dial. The reason for this is that the period of reciprocation 10 of the needle 2 is preferably constant, so that where the gage is comparatively coarse, the rate of advance of the dial must be increased to conform to the period of reciprocation of the needle. In my improved driving mechanism, I provide for this adjustment of dial speed by arranging the pawl 15 in such a manner that the length of its stroke may readily be changed to traverse a single tooth of the ratchet or several teeth 15 20 as the size of the dial gage may require. This adjustment may conveniently be effected by changing the position of the rod 20 with respect to the lever arm 19, a slot 23 extending longitudinally of the lever arm 19 being provided to permit the rod 20 to engage the arm 19 at different positions along the length of the latter, thus varying the extent of movement of the free end of the lever arm 19 and thereby of the pawl 30 35 15. The rod 20 is adapted to slide vertically in a rod guiding member 24, of which a top view is shown in detail in Fig. 4. This rod guiding member 24 is mounted to slide on suitable guide bars 25 which are rigidly supported by a fixed block 26. As shown in Figs. 1 and 4, I have provided means for actuating the rod guiding member 24 and locking the same in any desired position, said means including a threaded rod 43 passing 40 through block 26 and engaging a nut 44 which co-operates with the block 26 to limit movement of guide member 24 inwardly. The screws 45, Fig. 1, threaded at the sides of block 26 may be adjusted to 45 bear against the guide bars 25 when they occupy any desired position along the length of their respective grooves 27 in block 26. A compression spring 28 may conveniently be interposed between the pawl 15 and the lever arm 19 to press the pawl constantly 50 in tooth engaging position with respect to the ratchet 11.

Inasmuch as the looper-point dial 1 rotates continuously, it is necessary that the needle 2 be given a lateral motion, following the motion of the dial, in addition to the usual radial motion required in forming the loop. The needle may conveniently be mounted on one arm 42 of a bell crank 41 55 journaled on a shaft 29, said arm 42 being adapted to receive reciprocatory motion in the direction of the radius of the dial by means of a rod 30 having a cam strap 31 at one end adapted to engage a cam 32 60 mounted on the main power shaft 3. The

bell crank 41 is also slideable laterally upon the shaft 29. This lateral sliding of the bell crank may be effected by suitable means including a cam 33 mounted on the shaft 3 and actuating a rod 34 which engages one 70 end of a lever arm 35 fulcrumed at 36, the other end of the said lever arm engaging said bell crank 41. In order that the extent of lateral movement of the bell crank and the needle carrying arm 42 may be adjusted 75 to conform to different dial gages, the thrust of the free end of the lever 35 may be increased or diminished by changing the position of the fulcrum 36 in relation to the free end of said arm. For this purpose, the 80 arm 35 is provided with a slot 37 to receive a lug 36 mounted upon a pin 38 which is adapted to slide up and down in a slotted support 39. The pin 38 may be fastened in any desired position along the slot by suitable means, here illustrated as a wing nut 40 engaging a threaded portion of said pin. Thus, when the dial rotates continuously, the needle carrying arm receives a lateral thrust in the direction of motion of the dial 85 while the loop connecting stitch is being formed. As soon as the needle is withdrawn after the formation of the stitch, the needle carrying arm is moved quickly in the opposite direction so that the needle may again engage the next loop to form the next 90 stitch.

I claim as my invention:

1. In a machine for uniting knit fabrics, the combination of a looper-point dial, and means for rotating the same continuously, including a drive shaft having dial engaging means, a plurality of ratchets mounted on said shaft, and a plurality of pawls adapted to actuate said ratchets in overlapping sequence to effect continuous rotation of said shaft.

2. In a machine for uniting knit fabrics, the combination of a looper-point dial, means for rotating the same continuously, including a drive shaft having a dial engaging pinion and a plurality of ratchets mounted on said shaft in relatively stepped position, a plurality of pawls adapted to engage the respective ratchets in overlapping sequence, means to actuate said pawls, and means to adjust the stroke of said pawls to vary the rotation speed of the dial.

3. In a machine for uniting knit fabrics, the combination of a looper-point dial, means for rotating the same continuously, including a drive shaft having a dial engaging pinion and a plurality of ratchets mounted on said shaft in relatively stepped position, a plurality of pawls adapted to engage the respective ratchets in overlapping sequence, and means to actuate said pawls, and means for varying the rotation speed of the dial by varying the stroke of the pawls, including pawl carrying lever

arms and means for increasing and diminishing the thrust of said lever arms whereby the reach of the pawls may be varied.

4. In a machine for uniting knit fabrics, the combination of a looper-point dial, means for rotating the same continuously, including a drive shaft having a dial engaging pinion and a plurality of ratchets mounted on said shaft in relatively stepped position, a plurality of pawls adapted to engage the respective ratchets in overlapping sequence, and means to actuate said pawls including a main power shaft, cams on said shaft, pawl carrying lever arms each pivoted at one end and having a pawl at the other end, rods adapted to engage said pawl carrying arms, and means coöperating with the cams on the main power shaft to actuate the said rods.
5. In a machine for uniting knit fabrics, the combination of a looper-point dial, means for rotating the same continuously, including a drive shaft adapted to receive continuous motion of rotation, dial engaging means, a ratchet member operatively connected with said dial engaging means, a plurality of pawls mounted to engage said ratchet member in overlapping sequence, and means to actuate said pawls.
6. In a machine for uniting knit fabrics, the combination of a looper-point dial and dial rotating means including a plurality of connected ratchets, a plurality of pawls and means for operating said pawls to effect continuous rotation of said connected ratchets.

7. In a machine for uniting knit fabrics, the combination of a looper-point dial and dial rotating means including a plurality of con-

nected ratchets in relatively stepped relation and means to engage said ratchets successively in overlapping sequence to effect continuous rotation thereof.

8. In a machine for uniting knit fabrics, the combination of a continuously rotatable looper-point dial, a shaft, adjustable means connected with said shaft for actuating said dial at different speeds without a change in the speed of said shaft, and means for locking said adjustable means in position to operate the dial continuously at the required speed.

9. In a machine for uniting knit fabrics, the combination of means for rotating interchangeable looper-point dials adapted to accommodate fabrics of different mesh gages, thread needle supporting means having a fixed period of operation, and means coöperating with the dial rotating means for adjusting the speed of said interchangeable dials to conform to the fixed period of operation of the thread needle.

10. In a machine for uniting knit fabrics, the combination of means for rotating interchangeable looper-point dials adapted to accommodate fabrics of different mesh gages, a thread needle having a fixed period of operation and adapted to coöperate with the looper-points on said dial in the formation of fabric uniting stitches, and means for adjusting the dial rotating means to synchronize the speed of different dials with the fixed period of rotation of the thread needle.

In testimony whereof, I have signed my name to this specification.

C. K. POYNER.
